UNITED STATES PATENT OFFICE.

HENRY S. HALLWOOD, OF COLUMBUS, OHIO, ASSIGNOR, BY MESNE ASSIGNMENTS, TO THE HALLWOOD CASH REGISTER COMPANY, OF COLUMBUS, OHIO, A CORPORATION OF OHIO.

CASH-REGISTER.

1,078,920.

Specification of Letters Patent.

Patented Nov. 18, 1913.

Application filed November 4, 1899. Serial No. 735,748.

To all whom it may concern:

Be it known that I, HENRY S. HALLWOOD, a citizen of the United States, residing at Columbus, in the county of Franklin and 5 State of Ohio, have invented a certain new and useful Improvement in Cash-Registers, of which the following is a specification.

My invention relates to the improvement of cash registers of that class which are provided with mechanism for recording transactions and registering the amounts thereof.

The objects of my invention are to provide an improved cash register which shall be simple in its construction and positive in 15 its operation and results; to provide an improved mechanism employing one group of depressible keys and, in conjunction therewith, improved means for registering, indicating and successively adding the amounts 20 of the transactions, and printing on a continuous strip a detail record of the same wherein the character of the transaction, the amount and the operator are designated; to combine in the group of keys value, initial or identification and department keys and to provide, in conjunction therewith, means whereby a value or initial key when depressed through error may be returned without effecting the registration or record; 25 to provide, in conjunction with the group of keys, a no-sale key and means for preventing the depression of said no-sale key after a value key has been depressed; to provide means whereby a department key cannot be 30 depressed until a value key has been depressed; to prevent the depression or operation of value keys after a department key is depressed; to provide improved mechanism for indicating to the eye the amount 35 and character of the transaction, and mechanism for locking and releasing the same; to provide improved means for returning depressed keys to their normal positions through the closing of the cash drawer; to 40 provide an improved drawer, guide and locking mechanism; to provide improved means for setting the registering wheels to zero; to provide an improved record printing mechanism and to produce other improvements which will be set forth in detail hereinafter.

These objects I accomplish in the manner

illustrated in the accompanying drawings, in which

Figure 1 is a front elevation of that portion of my improved register on which is employed the group of keys. Fig. 2 is a similar elevation of that portion of the machine which contains the registering and printing mechanism. Fig. 3 is an elevation of that end of the machine that is opposite the printing mechanism. Fig. 4 is a sectional view on line *x-x* of Fig. 1 with the key counters omitted. Fig. 5 is a sectional view on line *y-y* of Fig. 2, looking 65 toward the left. Fig. 6 is a similar sectional view looking in the opposite direction from that indicated in Fig. 5. Fig. 7 is a front elevation of the printing attachment showing the same broken away or disconnected from the register body. Fig. 8 is a view in elevation of the printing attachment taken on that side which adjoins the cash register frame. Fig. 9 is a view in elevation of the outer side of the printing attachment. Fig. 10 is a sectional view of the printing attachment on line *z-z* of Fig. 7. Fig. 11 is a sectional view taken on line *t-t* of Fig. 7. Fig. 12 is a detail view in perspective showing one of the key lock plates and adjacent parts. Fig. 13 is a similar view in perspective of a portion of the upper base plate showing the drawer lock, drawer guide and key resetting mechanism. Fig. 14 is a view in perspective of an extension arm of one of the lock plates showing a pawl in connection therewith which is employed, in the manner hereinafter described, for preventing further movement of the lock plate. Fig. 15 is a similar view in perspective of a portion of the drawer lock. Fig. 16 is a similar view of a plate and arm which I employ in preventing the operation of the no-sale key. Fig. 17 is a vertical section taken through the fulcrum point of the key resetting lever. Fig. 18 is a plan view of a group of yoke arms and printing segments which I employ. Fig. 19 is a detail view in perspective of one of the value printing segments. Fig. 20 is a similar view of the department printing segment. Fig. 21 is a detail view in perspective of the pawls which prevent the reversal of the registering wheels. Fig. 22 is a similar view of a

portion of a registering wheel showing in conjunction therewith an adding and transfer mechanism. Fig. 23 is a similar view of the transfer operating device. Fig. 24 is a 5 similar view of a portion of a registering wheel showing the means connected therewith for resetting the same to zero. Fig. 25 is a similar view of one of the transfer operating fingers. Fig. 26 is a similar view 10 of a target releasing device. Fig. 27 is a view in elevation of the plunger employed in said target releasing device. Fig. 28 is an outer side view of the target operating cam, showing the same in an operated position. Fig. 29 is a vertical section on line 15 v v of Fig. 30 of a gear segment hub which I employ in the manner hereinafter set forth. Fig. 30 is a central vertical section of the same. Fig. 31 is a detail view in 20 perspective illustrating the registering wheel operating mechanism and showing the same in an operated position. Fig. 32 is a central sectional view through the head of the pawl carrying arm. Fig. 33 is a detail view in perspective of one of the yoke segment retaining fingers. Fig. 34 is a similar view of the printing platen and inking pad. Fig. 35 is a central longitudinal section of the paper strip receiving drum of 30 the printing attachment. Fig. 36 is a detail view in perspective of one of the drum disks. Fig. 37 is a sectional view on line s s of Fig. 35. Fig. 38 is a detail view in perspective of one of the key counters. Fig. 39 is a detail view in perspective of a cam head which I employ in the manner hereinafter described. Fig. 40 is a view in perspective of the end of one of the transfer rods and Fig. 41 is a detail view of a key 40 locking plunger.

Similar numerals refer to similar parts throughout the several views.

In carrying out my invention, I employ a suitable base frame and cash drawer casing 45 of which 1 represents the bottom plate or frame and 2 the top plate. Upon this base top plate is supported the main framework of the register body, to be hereinafter described, this main frame consisting particularly in vertical end frame standards 3 and 4, the latter being connected at intervals by frame rods, to be hereinafter described.

5 represents the cash drawer which is supported and adapted to slide within said base. 55 Journaled on the inner side of the side walls of the base casing are rollers 6 upon which bear the laterally projecting portions of plates 7 which are secured to the upper side of the drawer, the drawer being thus suspended on said rollers. In constructing the top plate 2 of the base, I form therein a longitudinal slot or opening in the direction of the length of the drawer, as shown at 8 in Fig. 13. The parallel edges which form the 65 sides of this slotted opening are rabbeted or

provided with longitudinal shoulders on which are adapted to slide the bearing projections or end tongues 9 of a transverse guide bar 10 which is connected with a top plate 11 with which the rear portion of the drawer is provided. At the forward end of the slotted opening 8, I secure to the base frame top plate 2, the forward end portion of a rearwardly extending spring strip 8^a, the latter being slightly inclined and projecting in the forward end portion of the slotted opening 8 (see Fig. 5). The guide bar 10 is provided at one end with an upwardly projecting hook finger 12, within which is pivoted a swinging dog 13. This dog 13 depends, as shown, so as to engage with a toothed bar or rack 14 which is supported upon the top plate 2 adjacent to one side of the opening 8. As shown in said Fig. 13, the position of the dog is opposite the rear end of the rack bar 14 when the drawer is closed. On the opposite end of the bar 10 is provided an upturned and rearwardly inclined finger 15, the latter being provided with an out-turned lug 16. To the rear side of the drawer is fulcrumed a bracket 17 which carries in its upper portion a journaled roller 18, the angle at which said bracket is supported from the drawer back being governed by an adjusting screw 19. As will hereinafter appear, the mechanism of the register is operated from the roller 18 on the drawer. The adjustable feature of said bracket enables the register to be adjusted so as to give the said mechanism its proper degree of movement. From the lower portion of the rear face of the bracket projects a curved spring strip 20. The rear side of the drawer is also provided with a conical boss 21 which is adapted, when the drawer is in its closed position, to engage and compress a short spiral spring 22 which projects forwardly from a lug 23 which rises from the rear portion of the base frame 1.

24 and 25 represent upper and lower transverse frame rods which extend across the front of the machine between the standards 3 and 4 and between which is mounted the key frame 26. This key frame consists of an outwardly curved or bowed external or face plate 27 which has formed on its inner side, at intervals inwardly projecting parallel wings or ribs 28, the latter being provided with radially arranged slotted openings 29. Each of the wings 28 has its inner portion provided with a laterally projecting curved shoulder 30 and this curved shoulder is provided on its outer side with stops or notches, as indicated at 31.

32 represent the value keys which are arranged one above the other and in parallel rows which extend from the right side of the key frame plate toward the left. To the left of these value keys are arranged a row

of initial or identification keys and, to the left of the latter, a row or partial row of department keys, the heads of which indicate the character of the transaction, such as "No-sale," "Received on account," "Cash" and "Charged." The heads of the value keys are numbered to represent different amounts, the row to the right being numbered from one to nine inclusive and indicating cents; the row to the left indicating cents in multiples of ten and the next rows to the left indicating dollars and tens of dollars respectively. The initial keys are indicated at 32^a and the department keys are indicated at 32^b. The stems of all of these keys, as indicated for the department and initial keys in Figs. 3 and 4 of the drawing, pass loosely through openings in the face plate 27 adjacent to the sides of the wings 28 and are provided on the inner side of said face plate with projecting transverse pins 33 which extend within the slotted openings 29 of the adjoining frame wing. The inner end portions of the key stems also extend 25 within radially arranged openings 32^c (indicated in Fig. 4), formed in the shoulder portions 30 of said wings, and between said shoulder portions 30 and the key stem pins 33 are interposed coiled springs 34 which 30 serve to normally retain the keys in their outer positions. The inner ends of the stems of the department keys 32^b are beveled, as indicated in Fig. 4. On the inner side of that shoulder 31 through which the beveled 35 inner ends of the stems 32^b are adapted to pass, I provide an elongated casing 35 which is curved to correspond with said shoulder, the inner side of said casing being provided at intervals with openings, which are indicated at 36, these openings being arranged at 40 points in line with said key stems 32^b. Within the casing 35, I provide a desirable number of transverse rollers or balls 37.

38 represent lock or detent plates of which 45 there is one for each set or row of keys, each of these lock plates having the general form of a battle ax and having their head portions at their rear sides fulcrumed on a central or main shaft 39 which extends between the end standards 3 and 4 of the main frame. In this manner the lock plates are so supported as to bring the forward portion of one of the same adjacent to the corresponding frame wing 28. This 55 forward edge of each of the lock plates is curved to conform to the curvature of the said wings and said curved edge has formed thereon hook shaped projections which are indicated at 40. The faces of these hook 60 projections are beveled, as shown in Figs. 5 and 12 of the drawing. As shown more clearly in Fig. 12 of the drawing, I provide each of the lock plates 38 in its upper and rear portion with an upwardly projecting trip arm 38^b, which is provided on

one side with a short projecting lug 38^c. The downwardly extending stem portions 38^a of the lock plates are, with the exception of the outer or department lock plate, connected through the medium of rearwardly extending connecting bars 41 with substantially bell crank shaped levers 42 which are journaled or fulcrumed on a frame rod 43 which extends between the end standards 3 and 4. The connecting bars 41 are connected with the shorter arms of said bell cranks, the longer arms thereof being, as indicated more clearly in Fig. 33, in the nature of forwardly extending and upwardly inclined or curved fingers 44 which are provided in their inner portions with a recess or shoulder 45 (see Fig. 33). 46 represent latch plates, the lower ends of which are fulcrumed on a transverse frame rod 47, there being one of these latch plates 46 for each of the lock plates 38. The latch plates as shown, are formed with curved or convex outer edges, these outwardly curved portions overlapping the hook recesses of the lock plates. Each of the latch plates 46 has its upper end portion and forward side provided with a recess 48 which is formed, as indicated respectively at 49 and 50, with upper and lower rear and forward offsets or pin seats. In the upper and rear seat 95 or offset 49 of each of the latch plates, normally rests a laterally projecting pin 51 of the adjoining lock plate, the engagement of said pins and offsets serving to normally retain the hook fingers of the lock plate 100 in such position that an inward movement of one of the keys of the corresponding set would result in the pin 33 thereof coming into contact with the inclined face of one of said hooks. Each of the latch plates 46 is provided with an upwardly projecting finger 46^b. The latch plates are normally held in their outermost positions through the medium of springs 47^a which are connected with the rod 47 110 and which exert an outward pressure on said latch plates, as indicated in Fig. 5. That latch plate which is at the extreme left of the key frame and which belongs to the department keys is, as indicated in Figs. 4 115 and 13 provided with an inwardly extending arm 46^b which terminates in a downwardly extending wedge shaped foot 52, said foot portion having on one side a laterally projecting shoulder, which is indicated 120 at 52^a and on the opposite side a stop projection 52^b. The wedge shaped foot or arm extension 52 has its lower end portion adjacent to the inner side of the lug 53 which rises from the upper side of the top base 125 plate 2, as is shown in Fig. 1. 54 represents an angular drawer latch or locking lever which is pivoted centrally at 55 to the upper side of the base plate 2. The rearwardly extending arm 54^a of this latch lever 130

has its end portion provided with a recess or shoulder 57 which, through pressure of a suitable spring 56, normally engages a lug 58 on one end of the drawer guide bar 10, this construction being more clearly shown in Fig. 15 of the drawing. Through this engagement the drawer is retained against outward movement, as will be hereinafter observed. The remaining arm of 10 the drawer latch, which is indicated at 54^a, terminates adjacent to the inner side of the wedge extension 52 of the arm 46^b. Upon the shaft 47 (see Fig. 13) is hinged a resetting yoke 59, the horizontal arm of which 15 is immediately beneath the stems 38^a or downward extensions of the lock plates 38. The yoke 59 is engaged by and rests upon the forward hook shaped end of a rearwardly extending trip lever 60, the latter 20 being fulcrumed in a short vertical post 61 which rises from the top base plate 2. This trip lever 60 has its rear and deeper portion thickened, as indicated at 61^a, to increase the weight and terminates in a downwardly and inwardly inclined end flange or shoulder 62. For reasons hereinafter set forth, the transverse pivot pin 60^a of the lever 60 is supported in a vertical slotted opening 60^b in the post 61, said lever 60 25 bearing upon a vertical spring 60^c which is contained in the hollow or socket of said post 61. (See Fig. 17.)

64 represents a lifting or lever plate, the short rearwardly extending arm of which is 30 fulcrumed on the pin 60^a and the vertical body of which is provided with a rearwardly inclined slotted opening 65. This lever plate is also formed with a laterally projecting angular wing 66 which consists of a 35 lower horizontal portion and a forwardly and upwardly inclined portion, the upper portion of the latter being in the path of the projection 16 of the drawer guide bar arm 15. The plate 64 is normally held or suspended in a desirable position through the medium of a forwardly extending arm 67 which normally bears upon the yoke 59. Upon the shaft 43, I fulcrum a yoke 68, one 40 end of the latter being provided with an arm 69 having a transverse cad pin 70 which works loosely in the slotted opening 65 of the plate 64, said pin being normally in the upper portion of said slotted opening. The remaining or outer end of the yoke 68 is 45 provided with a forwardly inclined arm 71, the out-turned lip 72 of which extends immediately beneath the lower end of that lock plate 38 which belongs to the department keys. The yoke frame 68, at its junction 50 with its arm 71, is provided with a downwardly extending arm 73 which normally bears against the forward side of the wedge shaped termination 52 of the arm 46^b.

65 Mounted to swing on the main shaft 39 opposite each of the key sets is a segment

74, the rim of the latter being in the arc of a circle which is eccentric to the shaft 39, said rim being provided with successively arranged notches or stop shoulders 75. The lower end of each of the segments 74 is provided with an extension 76 from which, with the exception of the department extension, projects laterally a pin 77, these pins being indicated in Fig. 1 of the drawing. Each of the segments 74 has formed therewith and extending rearwardly from its fulcrum point an arm 78 of a yoke piece 78, there thus being one of these yokes for each row or set of value, department and initial keys. The remaining side arms, or those arms of the 80 yokes 78 which are parallel with the arms 78^a and which are indicated at 78^b, are also fulcrumed on the shaft 39, each of said yoke side arms 78^b being subjected to the downward pressure of a spring 79. The yoke 85 arms 78^b are continued on the forward side of the shaft 39 in the form of a second set of yokes 80, the outer arms of which are fulcrumed, as indicated at 81 in Fig. 18 of the drawing, upon a short shaft 82 which is 90 in line with and forms substantially a continuation of the shaft 39, said shaft 82, being, however, on the outer side of the main frame standard 4. The yokes 78 are normally held in the elevated or partially elevated position indicated in the drawing, by the engagement of the pins 77 of the segments with the notches or recesses 45 of the fingers 44.

83 represents an outer gravity yoke, the 100 side arms 83^a and 83^b of which are also fulcrumed on the shaft 39. Connected with the side arm 83^b of the weighted yoke 83 is a downwardly extending finger 83^c which terminates in a forwardly curved or partial 105 hook shaped extension, as shown in Fig. 10. This finger 83^c is provided at a point in its upper and rear portion with a laterally projecting pin 83^d and at a lower point with a lateral half round pin projection 83^e. This 110 outer yoke 83 has one of its weighted side arms also subjected to the downward pressure of a spring, which is indicated at 84. The yoke 83 is provided on the inner end of its side arm 83^a with an upwardly projecting 115 arm 85, the latter being of a substantially T-form and its head thereof being in the nature of an oblong cam frame which is indicated at 86 and which is shown more clearly in Figs. 3 and 39. In constructing 120 the cam frame 86, I provide therein upper and lower slotted openings 87 and 88 which are separated by an intervening bar or rib 89, the latter projecting inward to form a continuous shoulder throughout its length. 125 It will be observed that the lower slotted opening 88 and, consequently, the underside of the bar or rib 89 is curved or bowed upward, which is also true of the slotted opening 87, with the exception of the forward end 130

thereof which is provided with an upward incline, as indicated at 87^a, and which results in the corresponding incline of the head or forward end of the bar or rib 89.

In the curved roller containing casing 35 heretofore described, a sufficient number of rollers or balls 37 are employed to fill the same less the space of one of said rollers, this space being sufficient when two of the rollers are separated to admit of the passage therethrough of one of the key stems. For reasons hereinafter set forth, it is desirable, however, that the rollers be normally locked against separation and the department keys thus locked against operation or depression until said rollers are released and capable of being separated. In order to thus lock said rollers against separation, I provide a plunger 90, the lower end of which is adapted to enter the upper and inner end of the casing 35 and to take up the space of one of said rollers, this construction being shown more clearly in Figs. 4 and 41 of the drawing, the latter view showing a frame spring 91 which extends into the forward channel of the plunger and holds the rollers out of the path of the plunger when the latter enters the roller casing. Upon a transverse shaft 92, I mount loosely or journal a lever plate 93 which is provided at intervals with forwardly projecting and downwardly inclined fingers 94, there being one of the latter for each of the lock plate arms 38^b, said arms terminating in rear of said fingers and the latter supporting the former. (See Figs. 4 and 12). The lever plate 93 is, as indicated more clearly in Fig. 4, jointedly connected with the upper end of the plunger 90 through an arm 95. I also fulcrum or mount upon the shaft 92 an upper lever plate, which I shall designate as a trip plate, and which is indicated at 96, this trip plate having on its outer end a downwardly extending arm 97, the lower end of which is jointedly connected with the rear end of a forwardly extending lock bar 98 which, in its outer portion, is provided with a longitudinal slotted opening 99, through which passes loosely the shaft 24. The outer extremity of the arm 98 is provided with a flaring head, which is indicated at 100 and which, when the arm 98 is in its most forward position extends within the path of a pin 101 which projects laterally from the no sale key stem 32^a. The horizontal portion of the plate 96 is provided on its forward edge with forwardly projecting and upturned fingers 102, there being one of these fingers for each of the plate extensions 46^a of the latch plates 46. The plate fingers 102 are, through the medium of the spring 103, normally pressed downward against the upper ends of the latch plate extensions 46^a. Fulcrumed on the shaft 24 on the inner side 65 of the lock bar 98 is a lifting lever 104, the

latter having its outer or forward end recessed on its upper side to form a hook termination, as indicated at 105, the point of said hook termination being normally supported beneath the pin 101 of the no-sale key stem. The inner or rear end of the lever 104 is provided with a slotted opening, as indicated at 106, this slotted opening receiving loosely the joint or pivot pin 107 of the plunger 90 and arm 95. As indicated more clearly in Fig. 12 of the drawing, I mount upon the shaft 24 the rotatable sleeve like projections 108 of a plate or bar 109. Each sleeve projection 108 is provided with a recessed or cut away portion 110, the latter being arranged at such point on the periphery of the sleeve as to normally receive a portion of the top hook of the adjoining and corresponding lock plate 38 when the latter, in the manner hereinafter described, is forced slightly upward. The sleeve projections above described are normally held in the positions mentioned through the medium of a spring 111. At its outer end the plate or bar 109 is provided with a rearwardly extending arm 112 which is provided with an angular slotted opening 113. Through this slotted opening, and normally resting in the inner and vertical portion thereof, projects a pin 114, the latter projecting laterally from the upper portion of the upper extension 46^a of the department latch plate 46. Upon the shaft 24 are mounted separated bell cranks or angular fingers 115, each of the rearwardly extending arms thereof being, as indicated at 115^a, provided with a hook shaped termination or downturned tooth. These toothed terminations of the bell crank arms normally rest upon the upper side of the laterally projecting lugs 38^c of the lock plate extensions 38^b. The remaining or outer arms of the bell cranks 115 extend upwardly, as indicated at 116 and engage the forward side of the plate 109.

Supported on that side of the key frame on which is employed the department keys are key counters or registering devices 199, one for each of the department keys, and each of which consists of a cylindrical case having a suitable or well known registering or counting mechanism therein which is adapted to be operated by the partial rotation of the central shaft 200. With each of the key counter shafts 200 is connected an arm 201 which is provided with an elongated slot 202 (see Fig. 38). The slotted openings in the arms 201 are adapted to receive the projecting ends of the department key pins 101 (see Fig. 3). As indicated at 203, I employ below the set of counters 199 a similar counting device, the shaft of which is provided with an outwardly extending arm 204 which through 130

the medium of a connecting rod 205 is jointedly connected with the arm 85. This last described counter 203 is intended, as will be shown hereinafter, as a drawer counter or register.

117 represents a transverse shaft which extends between the upper ends of the frame standards 3 and 4. Upon this shaft are rotatably mounted indicating wheels or targets 118, there being one of the latter for each row of depressible keys. Each of the indicating wheels or targets carries on one side thereof a pinion wheel 119, said pinion having fixed thereto a toothed wheel or ratchet 120. Rotatably mounted in the framework and extending in front of the indicator wheels is a shaft 121, said shaft having extending therefrom at intervals inclined spring pawls 122, the upper ends of which engage the teeth of the ratchet wheels 120 and retain the latter against their reversed rotations. Supported horizontally beneath the indicator wheels is a shaft 123 on which are fixed at intervals disks 124 which are provided with hubs or short sleeves 125. (See Figs. 29 and 30.) Inclosing each of the disks 124, and forming in conjunction therewith a circular casing about the hub 125, is the cup shaped lateral projection 126 of a gear segment arm 127, the latter extending outwardly and having its gear segment or head 128 gearing with one of the pinions 119. Within the casing formed by the parts 124 and 126 I provide about the hub 125 a coiled spring 129, one end of the latter being connected with said hub and the remaining end connected with the portion 126. Each of the gear segment projections 126 is provided with a rearwardly projecting arm 130. Jointedly connected with each of these arms is the upper end of a downwardly extending connecting rod or bar 131, the lower and longitudinally slotted end portion of which is, through the medium of a pin 132, connected with an upwardly projecting lug 132' of the corresponding yoke side arm 78.

133 represents a bar or arm the upper end of which is connected with the outer end 50 of the shaft 121 (see Figs. 3 and 28). This shaft arm, which extends downward and inclines rearwardly, has on its lower end portion an outwardly projecting pin 134, said pin being adapted, in the manner herein-55 after described, to travel about the central bar 89 of the cam frame 86. As shown more clearly in Fig. 3, I pivot to the side of the frame standard 3 in its upper portion one end of a short spring actuated bar 135 which 60 extends rearwardly and which, through the pressure of one end of a suitable spring 136, has its out-turned rear portion normally bearing upon a transverse shoulder of said frame standard. The spring 136, which is 65 wound upon the shaft 121, has its remaining

end exerting a rearward pressure on the arm 133.

As shown more clearly in Fig. 26 of the drawing, I employ a plunger 137 which extends through an opening in the upper portion of the frame standard 3 and a tubular inward projection 3^a thereof. The stem of the plunger 137 within said tubular frame projection is surrounded by a coiled spring 138 which normally retains said plunger in its outer position. The outwardly projecting head of the plunger is rounded or beveled on one side, as indicated. The inner end of the plunger stem passes loosely through an elongated slot 139 which is formed in a forwardly extending bar 140, said plunger stem having an enlarged head 137^a. The forward end of the bar 140 is pivotally connected with the upper portion of the department latch plate extension 46^a. This bar 140 is provided on its inner side with a shoulder 141 from which point toward its inner end said bar decreases in thickness to produce a substantially wedge shaped termination.

Upon the main shaft 39, I mount to the right of the key frame a set of registering wheels, which are indicated at 142. In order to distinguish these wheels, I will designate the same successively from right to left as cents, dimes, dollars, tens of dollars and hundreds of dollars wheels. Each of said wheels is provided on one side with the projecting teeth portions of a ratchet wheel, as indicated at 143, while the peripheries of all the wheels, with the exception of the hundreds of dollars wheel, are numbered with successively arranged groups of successively arranged figures from naught to nine inclusive. The hundreds of dollars wheel at the extreme left is numbered with figures running from naught to ninety-nine inclusive. In constructing each of the registering wheels I form on the periphery thereof between the naught and nine of the successive sets of numbers, outwardly projecting lips 144. On the hundreds of dollars wheel, however, but one of these lips is provided, that being arranged between the naught and one characters. On the inner side of the rim of each of the registering wheels I provide at points opposite the lips 144 a tooth or shoulder 145, the latter having an inclined inner face, as shown.

146 represents a yoke frame which swings 120 from the main shaft 39 and which embraces the forward portions of the registering wheels. Extending in front of the registering wheels between the side arms of the yoke 146 is a shaft 147 on which are mounted dogs or arms 148, there being one of the latter for each of the registering wheels. These arms or dogs 148 extend inward and upward between the registering wheels and are provided with outwardly bent ends 149 130

which are adapted to engage the shoulders 145, said arms or dogs being retained in this engaged position through the medium of springs 150 which are mounted upon the shaft 147 and the ends of which respectively engage the yoke 146 and press downward the outer ends of said dogs.

151 represents pawl carrying arms, the inner ends of which are journaled on the shaft 39 and the rearwardly extending portion of each of which carries a spring actuated pawl 152. The number of pawl carrying arms corresponds with the number of yokes 78 and the pawls of said arms engage respectively with the teeth of the cents, dimes, dollars and tens of dollars wheels. In the formation of each of the pawl carrying arms 151, I fulcrum in the channeled upper side of the outer portion thereof an angular pawl locking lever 153, the latter being in the nature of a bell crank and consisting in a forwardly extending lower arm portion 153^a and an upwardly and forwardly curved and longer arm portion 153^b. As indicated more clearly in Fig. 32 of the drawing, the bell crank 153 is, at the junction of its two arms, provided with a short rearward extension 154 which is normally lifted by a spring 155 which is supported in a socket of the arm 151. Each of the pawl carrying arms has depending from its outer portion a supporting stem 156, these stems resting respectively on the yokes 78. In constructing each of the spring actuated pawls 152, I preferably recess the outer edge thereof as indicated at 152^a. Through the action of the spring 155, the arm 153^a of the bell crank 153 normally engages said notch 152^a and locks the pawl in engagement with the teeth of the registering wheel. Rotatably mounted upon a transverse shaft 157 above the pawl carrying arms is a yoke or cam sleeve 158, the rounded central bar of the latter normally projecting upward, as indicated in Figs. 4 and 6. This yoke is provided with a reduced extension, indicated at 159 which works loosely in a slotted opening 160 of a bowed bar 161, the latter extending forwardly and upwardly and being jointedly connected at 161^a with a downwardly extending arm 162 of the shaft 121.

158^a is a spring which connects the shaft 157 with said yoke and presses the latter rearwardly.

55 Suitably journaled in the framework of the machine above the registering wheels, and arranged in the arc of a circle that is concentric with respect to said wheels, are transverse shafts or rods 163. On each of these shafts is secured a bracket or block 164 (see Fig. 22), these brackets being arranged out of alinement with each other, one above each of the first four registering wheels. Each of the rods 163 adjacent to its inner end has projecting downwardly

therefrom a short depending trigger 165, the inner side of this trigger being beveled, as shown more clearly in Fig. 25 of the drawing.

166 represent angular bars, the lower end of the substantially vertical arms of which are fulcrumed on the shaft 39, one of said lever arms being thus fulcrumed between each pair of the registering wheels. The rearwardly extending arm 166^a of each of these angular bars has its end portion provided with a laterally projecting pin 167 which loosely engages an end notch or recess 168 in a projecting lug 169 of the corresponding bracket 164. To the upper portion of each of the vertical arms 166 is fulcrumed the lower portion of a catch lever 170, the latter being provided opposite its fulcrum point with a forwardly projecting pawl arm 171 having a downturned end portion and being provided in its upper portion with a short forwardly projecting arm 172. To each of the rearwardly extending arms 166^a is pivoted, as indicated at 173, a forwardly extending hook bar 174, the hook shaped forward end of which is provided on its inner side with an angular recess or notch 175 which is adapted to engage the correspondingly shaped top and forward face of the head of the catch lever 170. The above described engagement of the hook bar and catch lever head is normally retained through the medium of a coiled spring 176 which connects said hook and the lower portion of the catch lever body. It will be observed that the engagement last described also serves to elevate the pawl arm 171 out of the path of the teeth of the adjoining registering wheel. In rear of its pivot point the hook bar 174 is provided with a laterally projecting pin 177. With the upper side of this pin contacts the rearwardly inclined lateral shoulder of a pawl bar 178, the latter being fulcrumed centrally upon a transverse frame rod 179.

In Fig. 22 of the drawing, I have shown portions of two adjoining registering wheels and we will assume that the portion nearest the eye is the dimes wheel and the other the cents wheel. While the pawl arm 171 is normally supported above the teeth of the dimes wheel, it will be observed that the pawl bar 178 has its forward and inclined portion retained in the path of the projecting lug 144 of the adjoining cents wheel. In order to normally retain the upper arm 166^a of the lever 166 and hook bar 174 in their rearmost position, I employ a coiled spring 179^a for the outer end of each of the rods 163, these springs being indicated in Figs. 2 and 40. One end of each of said springs is connected with the stationary framework and the remaining end portion thereof is connected with and coiled about the end of one of said rods, the tendency of

said springs being to turn the rods rearwardly.

180 represents an angular arm or lever which is rotatably mounted on the shaft 39 and which consists of a rearwardly extending arm 181 which terminates in a downwardly extending portion 182. This lever is further provided in its inner end portion with an upwardly extending arm 183 from which extends forwardly a curved branch arm 183^a. At the junction of the rearwardly and downwardly extending arms 181 and 182, the lever is provided on its upper side with an upwardly projecting hook finger 184. As indicated at 185, the arm 182 terminates in a horizontal foot portion which is adapted to contact with the periphery of the drawer or roller 18 and the heel of which is adapted to engage the rear side of the drawer cross bar 10. The upper side of the outer portion of the lever arm 181 forms a support for the rear horizontal bars of the yokes 78 and 83.

Journalized in front of the transfer mechanism is a transverse shaft 186 from which depends an angle plate 187. Connected with the shaft 186 is an inwardly and downwardly extending finger 188, the lower termination of which is at a point on the outer side of the inner registering wheel. The upper arm 183 of the lever 180 is channeled on its outer face and in the lower portion of said channel is hinged at 189 the lower end of a trip bar 190, the latter having its upwardly extending end portion beveled and inclined as indicated at 191. This trip bar, which is shown more clearly in Fig. 23 of the drawing, is normally pressed outward by a spring 192, the outward movement of said bar within its channel being limited by a transverse pin 193. The spring actuated and normally outwardly pressed trip bar thus produced has its upper and beveled end portion retained in position to successively contact with the triggers 165 when the lever 180 swings on its shaft. Upon a transverse rod 24 which extends in front of the upper portion of the registering wheels are spring actuated dogs 195 which are respectively retained in engagement with the teeth of the registering wheels (see Fig. 21).

196 represents a rearwardly extending horizontal stop bar which is rigidly mounted on the shaft 24. Upon a transverse rod 197, in front of the registering wheels, I mount the lower end of an inwardly inclined spring stop plate 198, the inturned termination of which is adapted to be pressed into the path of the registering wheel lugs 144, said stop plate being suitably notched or formed to prevent engagement thereof with the ratchet teeth of the registering wheels.

Supported upon a lateral extension of the top base plate of the machine is a printer frame, of which 206 and 207 represent the

outer and inner sides respectively. The heretofore described transverse rod or shaft 82 connects the upper ends of vertical extensions of said frame sides, and upon this rod are fulcrumed or journaled the rearwardly extending parallel arms of the yokes 80. Each of said yoke arms is provided at its fulcrum point with a downwardly extending printing segment, these segments being indicated respectively at 209, 210, 211, 212, 213 and 214, there thus being one of these segments for each of the rows of initial keys and the row of department keys. The printing surfaces or faces of the segments of the value keys are provided with type or printing projections which run from naught to nine inclusive, while the letters, which are the subject of the type projections of the segment 214, indicate the different departments. The printing segment 213 carries on its face type letter projections corresponding with those in the initial bank of keys. Beneath these segments is rigidly supported between the side frames a horizontal frame 215, the latter consisting of vertical and parallel side plates 215^a and a central horizontal plate 216 which is provided with a central opening. Between the rear ends of the side pieces 215^a, and in rear of the plate 216, is journaled a transverse roller 217 and, between said frame side pieces and immediately in rear of the forward section of said plate 216, is journaled a feed roller 218 which is preferably of rubber or similar material. Journalized on the inner side of each of the side pieces 215, and adjacent to the forward side of the roller 218, are oppositely located friction rollers 219, the peripheries of which are, as indicated in Fig. 7, roughened or knurled. Above the roller 218, and in rear of each of the rollers 219, I provide inwardly projecting guide pins 220.

221 represents a platen lever or platen carrying arm, the downturned rear end of which is fulcrumed on a transverse shaft 222 which extends between the rear and lower portions of the frame sides. At its inner side, the rear end of the platen lever is provided with an upwardly extending rigid arm, which is indicated at 223. On the upper end of this arm is fulcrumed the rear end of a forwardly extending ink pad carrying bar 224, the forward downturned end of which carries a horizontal ink box 225 which, in its forward end portion and upper side is provided with a transverse slotted opening in which is inserted a transverse ink pad 226, said ink pad case normally resting on the upper side of the rear section of the frame plate 216. The forward upturned end of the platen lever supports transversely a platen head or body of suitable yielding material, as indicated at 227. This forward end or head of the platen lever is provided

on its inner side with a laterally projecting pin 228.

229 represents a trip lever, the lower end of which is fulcrumed in connection with the lower portion of the inner side frame 207, from which point said lever normally extends upward and rearward and terminates in the form of a curved trip finger, as shown more clearly in Fig. 8. Through the medium of a short bar 230, a toggle joint connection is effected between the lever 229 and the pin 228. A forward pull is normally exerted on the lever 229 through the medium of a coiled spring 231. As indicated at 232, I employ a latch bar, the upper end of which is pivotally connected with a vertical standard of the inner frame side 207 and the lower end portion of which is provided on its rear side with an angular recess, which is indicated at 233. The recessed portion of the latch bar is normally retained in contact with the projecting portion of the pin 228 through the medium of a spring 234, one end of which engages the forward side of the latch bar and the remaining end of which is connected with the frame standard.

Rising from the inner frame piece 207 at the rear end thereof, is a standard or upright arm 235, upon a projecting pin of which is mounted a paper carrying roll or roller 236. Projecting outwardly from a forward extension 207^a of the frame side 207 is a pin 237, upon which is journaled the central tubular portion of a paper receiving reel 238. This reel consists of a central tubular portion and inner and outer flanges 238^a and 238^b, the flange 238^b being formed with said tubular portion, while the inner flange, as shown in Fig. 36 is in the form of a disk 40 which surrounds the pin 237 and which is provided with an inwardly projecting lug 238^c in the form of a tube segment and which engages the correspondingly shaped recess 238^d of the reel tube. In order to retain this reel upon its pin, I provide a spring strip 239, one end of which is secured within a recess 240 of the pin 237 and the remaining outwardly sprung shouldered end of which engages the outer flange of the reel (see Fig. 35). I also provide a paper guide bar 241, which is in the nature of a strip extending parallel with and adjacent to the periphery of the reel tube, said strip being supported in this position by having one of its ends connected with the outer flange of the reel. On the inner side of the inner reel flange 238^a, and between said flange and the frame extension 207^a, I mount, on a reduced portion of the pin 237, a ratchet wheel 242, the latter being provided with an outward extension which also surrounds said pin and which terminates in a cup shaped casing 243, the outer edges of which adjoin the inner reel flange 238^a. Surrounding the pin 237 and within the cup

body 243, I provide a coiled spring 244, one end of said spring being connected with the inner side of said cup body and the other end thereof being connected with the reel flange 238^b.

242^a represents a spring pressed pawl which is pivotally connected with the printing attachment framework and the tooth of which engages the teeth of the ratchet wheel 242 and prevents the latter from reversed rotation. Upon the shaft 218^a, which carries the roller 218, (see Fig. 10) I also mount a ratchet wheel 246 and the teeth of which are arranged at desirable intervals one from the other, said teeth being adapted to be engaged by a pawl 247 which is pivotally connected with the printer framework. The teeth of the ratchet 246 are also adapted to engage on the underside of said ratchet wheel with the tooth of a pawl 248, one end of which is pivoted in the upwardly projecting portion of a feed bar 249. As indicated more clearly in Figs. 10 and 11 of the drawing, the pawl 248 is provided with an end projection 250, with which is adapted to engage the upwardly projecting hook finger 251 of said bar 249. Between the pawl 248 and the upper side of said bar, I provide a coiled spring 252 which normally retains said pawl in an elevated position, as shown. In constructing the feed bar 249, I provide the same with a forward extension which terminates beneath the ratchet 242 and which has pivoted in an upwardly projecting lug thereon one end of a spring elevated pawl 253, the upwardly projecting tooth of said pawl being thus retained in position permitting of its being engaged with the teeth of said ratchet wheel by an upward movement of said feed bar extension. As indicated at 254 in Figs. 9, 10 and 11, the feed bar is connected with the frame portion 207 through the medium of a pin which extends outwardly from said frame through a longitudinal slotted opening 255 in said feed bar. The rear end portion of the feed bar is provided with an extension in the form of an upwardly curved rod 256, the outer portion of the latter working loosely through a suitable keeper 257 which projects from the rear portion of the frame 207. This curved rod extension of the feed bar, between said keeper and the rear end of the feed bar body, is surrounded by a coiled spring 258 which tends to normally force the feed bar to its most forward position. On the rear portion of the spring actuated rod extension 256, I provide said rod with an adjustable step lock 259 the latter being pivotally connected as indicated at 260 with the slotted lower end of a swinging bar 261, the upper end of which is pivoted in the upper end portion of the frame standard 235. On the inner side of the frame side piece 207, and in the upper and rear portion thereof, I

5 pivot one end of a bar 262, the latter extending forwardly and being normally supported on a projecting frame pin 263. The forward end portion of the bar 262 is provided on one side with a lateral extension 10 or branch 264 which projects beneath the inking pad case 225. The bar 262 is also provided in its outer end with a laterally projecting trip pin 265, the lower and rear side of which is provided with a rounded 15 surface, as indicated more clearly in Fig. 8 of the drawing.

In order to illustrate the operation of my improved cash register and explain the 15 utility of the various parts which have been described, we will assume that the cash drawer is closed, that the value, initial and department keys are in their outer positions and that the indicator or target disks 18 20 display on their forward sides the cipher characters. One of the value keys being depressed, for instance, the five cent key, the laterally projecting pin 33 of said key stem comes into contact with the inclined face 25 of the corresponding hook finger 40 of that lock plate 38 which belongs to the cents bank of keys. This contact results in a slight upward movement of said lock plate, permitting the pin 33 to pass the lock plate 30 hook and, at the same time, raising the lock plate pin 51 out of its seat in the recessed offset 49 of the latch plate 46. This disengagement of the pin 51 and latch plate offset is produced by the contact of the key stem 35 pin 33 of the operated key with the curved forward edge of the corresponding latch plate 46, the latter being thus pressed inwardly and the lock plate dropping downward by gravity until the pin 51 is in the recess off- 40 set 50. It is evident that the dropping of the latch plate results in the engagement of one of the hook fingers with the pin 33 of the depressed key and locks said key against outward movement. The downward 45 movement of the lock plate above described results through the connection of its extension 38^a with the bar 41 in the dropping of the finger 44 connected therewith until its notch or recess 45 is out of the path of the 50 pin 77 of the corresponding segment 74. In this manner said segment when its yoke is released from support is free to move upward until one of its teeth or shoulders 75 contacts with the inner end of the depressed 55 key stem, the degree of upward swinging movement of the segment being thus limited by the key depressed. In the operation above described, it will be observed that the inward depression of the latch plate 46 must 60 result in its upper extension 46^a moving under one of the projecting fingers 102 of the rocking plate 96 and in raising the latter. The swinging movement thus imparted to said plate 96 results, through the 65 connection of the arm 98 therewith, in mov-

ing the inclined head 100 or the outer end of the latter, under the pin 101 of the no sale key 32^b, thereby preventing a depression of the latter after the value key has been depressed. The downward movement 70 of the lock plate, caused by the pin 51 thereon falling into the recess 50 of the latch plate, also results in the extension arm 38^b thereof contacting with one of the inclined fingers of the journaled bar or plate 75 93 and imparting an upward swinging movement to the latter. Through the connection of the plunger 90 with this plate or bar 93, this upward movement of said plate results in said plunger being withdrawn 80 from its position in the end of the ball channel 35, thus permitting a department key, such for instance as the cash key, being depressed and allowing the inner end of its stem to pass between two of the balls or 85 rollers 37, thence through one of the case or channel openings 36 and into the path of one of the teeth of the department segment 74. The depression of the department key results, through the connection of the department key latch plate extension 46^a with the frame plate 109, in the pin 114 (see 90 Fig. 12) moving inward to the end of the longer arm of the slot 113 in the connecting piece 112 and in forcing the latter and the frame plate 109 with which it is connected 95 rearwardly. This rearward movement of said frame plate results, first, in releasing the upturned forward ends 116 (see Fig. 14) of the latch bars 115, permitting said latch 100 bars to drop rearwardly and causing the hook end 115^a of one of the same to drop over and engage the lateral lug 38^c of the extension 38^b of that lock plate which belongs to the set of keys, one of which is depressed. In this manner all the remainder 105 of the value keys of said set are locked against depression after the department key has been depressed.

The normal position of the frame plate 110 109 is such that its recesses permit of an upward movement of the lock plates, but in the operation just described said frame plate is swung rearwardly so as to cause the unrecessed portions of the hubs or sleeves of 115 said frame plate to prevent upward movement of the lock plates by contact therewith. By this means it is obvious that the depression of a department key also so locks the lock plates as to prevent operation of any of the value or initial keys after the operation of said department key. From the above description, it will be seen that means are provided for locking the lock plate which belongs to that bank or set 120 which contains a depressed key, in as much as both the engagement of the latch piece 115 with the lock plate lug 33^c and the contact of the upper teeth of the lock plates 125 with the unrecessed portions of the hubs ac- 130

complishes this purpose. This additional lock, however, is provided in order to more positively insure the locking of the keys in the bank which contains the depressed key.

6 Owing to the connections of the department key pins 101 with the slotted shaft arms 201 of the key counting devices 199, it will be observed that at each depressing of a department key, an operation of one of the counter operating shafts is produced, thereby disclosing in the usual manner through the slotted opening of the counter casing, figures indicating the number of times said department key has been depressed.

15 In case of an error in depressing one of the value or initial keys of either set or bank and the discovery of such error before the depression of the department key, it is obvious that the mistake may be rectified without imparting a registering operation to the machine by subjecting another key in the same bank or set to a partial depression. Through this movement of the last mentioned key stem, the contact of its pin 33 with a hook finger of the corresponding lock plate, results in raising said lock plate sufficiently to allow the formerly depressed key to escape through action of its spring to its former position and, owing to the incomplete depression of the last key operated, said last operated key will also return to its normal position. It will be seen, however, that this applies to cases where a key of the wrong bank has first been depressed or where the operator does not desire to complete the registration. In case the error above mentioned should arise from the operator having depressed a wrong key of a set, it is evident that the proper key might be depressed before the depression of a department key which would return the first depressed key to its normal position.

40 In order to provide, in the manner hereinafter described, not only a record of the amount of the transaction and its character but to indicate the operator or particular clerk or individual making the transaction, the operator having depressed a value key depresses that initial key, which we will assume to be "A," by which he is identified, thus setting the initial key segment 74 for upward rotation in the manner prescribed for the cents key segment.

45 When either the no sale or department key has been depressed, and the department latch plate 46 rocked on the shaft 47, it is obvious that the wedge termination 52 of the latch plate extension 46^b will be driven downward between the frame lug 53 and the forward end of the drawer latch bar arm 54^b, resulting in forcing the latter away from the lug 53 and imparting a swinging motion thereto which will cause a disengagement of the latch arm 54^a with the lug 58 of the drawer cross bar 10. In this manner it will be seen

50 that the drawer is released or unlocked and permitted to slide to the open position, first through the pressure of the spring 22 and second through the pressure of the arm 182 of the lever 180, the latter receiving its impetus partially from gravity and partially from the pressure of the outer weighted yoke 83. In the forward or outward movement of the cash drawer, its transverse guide bar 10 comes into contact with the underside of the spring strip 8^a, the frictional contact thus produced serving to aid in stopping the outward movement of the drawer without shock. It will also be observed that in the outward movement of the drawer, the dog 13 is drawn over the toothed upper surface of the rack bar 4, said dog inclining rearwardly. In case, however, an attempt is made to close the drawer before the dog leaves the forward end of said rack bar, it is obvious that an engagement of the rear side or edge of said dog and a tooth of the rack bar will occur which will effectively prevent a closing movement of said drawer. In the opening movement of the drawer, it will be seen that the out-turned end 16 of the guide bar arm 15 will contact with and move under the inclined lateral projection 62 of the trip lever 60 and that said projection 16 will also travel over the inclined forward portion of the lateral extension 66 of the plate 64.

55 The downward and forward swinging movement of the lever 180, which was occasioned by the opening of the drawer, results in removing the support from the yoke frames 78 which belong to the cents, initial and department banks of keys which we have heretofore assumed to have been depressed. This downward swinging movement of said yoke frames, results in relieving from support the cents pawl carrying arm 151 and in the dropping of the pawl 152 of the latter downward and over a certain number of teeth of the cents wheel, which in the present instance is limited to five teeth by the limited movement of the segment 74. As will be seen by the operation hereinafter described, the dropping of the pawl carrying arm over the teeth of a registering wheel cannot be accomplished until the locking arm 153 is, in the manner to be set forth, disengaged from the pawl 152. The depression of the department key, heretofore described, through which the unlatching and opening of the drawer is accomplished, results, through the connection of the extension 46^a of the department latch plate (see Fig. 26) with the pin or plunger 137, in a rearward movement of the bar 140 and, through the wedge shape of the inner end of the latter, in the pin or plunger 137 being moved inwardly, thus releasing the arm 133 and admitting of the latter swinging rearward until it contacts with the lat-

60 70 75 80 85 90 95 100 105 110 115 120 125 130

eral projection of the stop arm 135. It will thus be seen that, at the first motion of opening the drawer, a partial rotary motion is imparted to the shaft 121 which releases the 5 pawls 122 from engagement with the ratchet wheels 120 of the targets or indicators 118.

The continued opening of the drawer and the consequent falling of the weighted yoke 83 results in the cam shaped head 86 of the 10 frame 85 swinging rearwardly and in the laterally projecting pin 134 of the arm 133 being made to change its position from the rear end of the lower slotted opening 88 to the forward end of the upper slotted opening 87 and into the forward end of said frame head 86. In executing this movement, it will be seen that the path of said pin 134 is about the outer or rear end of the rib or bar 89 and over the upper side of the 15 latter. Owing to the upward incline 87^a of the slotted opening 87, it will be observed that the movement of the frame 86 which brings the pin 134 into the inclined end portion 87^a of the slot 87, results in imparting an additional swinging movement to the arm 133, thereby increasing, by the contact of 20 said arm with the stop piece 135, the spring pressure of the latter which results in the pin 134 being forced a sufficient distance 25 downward on the forward end of the rib 89 to insure its traveling beneath the latter when the cam frame is returned to its normal position. When the ratchet wheels are released from engagement with the pawls 30 35 122, as hereinbefore described, the action of the springs 129 of the gear segments 128 are such as to throw said segments forwardly until they bear upon a transverse frame stop rod 128^a (see Fig. 4). In this 40 manner the value targets or indicator disks are rotated until the naught signs are read from the front thereof, the initial indicator disk displaying the dollar sign and the department disk showing blank. It is evident 45 that the above described movements of the gear segments will cause the rods 131 to be raised until the pins 132, which connect the same with the yoke lugs 132^a, are in the lower ends of the slotted openings of said 50 rods.

It will be observed that the above described operation of the targets is occasioned at the first motion of opening the drawer, but, on the continued opening movement of 55 said drawer, it will be observed that the dropping of the yokes 78 which belong to the depressed key banks will result, through the connecting rods 131, in the gear segments 128 turning the corresponding targets so 60 that, in the case described, the cents target will display from the front the numeral 5, the initial target will display the initial letter A and the department target the word cash. The partial rotation of the pawl carrying shaft 121, which was occasioned by

the first of the drawer opening operation heretofore described, also results, through the connection of said shaft with the bar 161, in moving the latter rearward until the reduced termination 159 of the cam yoke 79 158 is in the forward end of the slotted opening of said bar 161, said bar thus exerting a pressure on said cam yoke which tends to turn the latter rearward. At the dropping of the yokes heretofore described, which immediately follows the first operation of opening the drawer, the cam yoke 158 is by the dropping of the pawl carrying arms 151 permitted by pressure of the spring 158^a to turn and press the arms 153^a of the bell 80 cranks 153 rearward until the arms 153^a thereof are out of contact with the pawls 152, the latter being thus permitted to drop downward over the teeth of the registering wheels. 85

At the first motion of closing the cash drawer and the consequent beginning of the lifting movement of the weighted yoke 83, it is evident that the cam frame 86 will swing toward the front, with the result of causing the pin 134 of the arm 133 to travel down and about the forward end of the central rib 89 of the cam frame, thereby swinging said arm 133 forwardly and rotating the shaft 121 sufficiently to cause an engagement 90 of the pawls 122 with the ratchet wheels 120. In this manner it will be seen that at the first motion of closing the drawer, the targets are locked in the positions previously described. The continued closing movement of the drawer also results, through the upward movement of the dropped yokes and the engagement of the pawls 152 of the dropped pawl arms with the registering wheels, in said registering wheels being 95 turned forwardly distances limited by the movement of the yokes. It will also be observed that the rotation of the shaft 121, which is produced by the first closing movement of the drawer will, through the bar 161, return the cam yoke 158 to its normal or forward position, thereby permitting the arms 153^a of the bell cranks 153 dropping into engagement with the pawls 152 and, through this engagement, preventing any 100 overthrow of the registering wheels from 105 impetus. 110

In the continued closing movement of the drawer, it is evident that the projecting pin of the arm 133 will travel downward over 115 the forward end of the cam frame rib 89 and thence through the slotted opening 88 to the opposite end of said rib. In the forward swinging movement of the bar or arm 133 above described, said bar, by contact with the beveled side of the projecting end portion of the plunger 137, will force said plunger inward, but said plunger will be immediately returned to its outer position through the pressure of its spring 138 on the pass- 120 125 130

ing of said arm. As the drawer is closed, it will be seen that the projecting end arm 15 of the drawer guide bar 10 will contact with and travel against the underside of the inclined forward portion of the flange 66 of the rocking plate 64 with the result that said plate 64, is tipped until the pin 70 is in the outer end of the slotted opening 65 and sufficient pressure is exerted on said pin 10 to tip or swing the yoke 68. This tipping or swinging of said yoke and the consequent upward movement of its arm 71, results in a raising of the department lock plate 38 until its pin 51 is again in the upper offset 49 of the adjoining latch plate recess 48. This upward movement of the lock plate raises the hook fingers thereof until the laterally projecting pin 33 of the previously depressed department key stem is released 15 and said key is allowed to return to its outer position. As the drawer continues its inward movement, the guide bar arm projection 16 comes into contact with the upper side of the incline projection 62 of the trip lever 60, thus raising the forward end of said trip lever and lifting the resetting yoke 59 until the lock plates of the value and initial keys are raised and said keys are thereby reset. As the drawer reaches its 20 closed position, the lug 58 of the guide bar 10 moves into engagement with the recess 57 of the spring actuated latch bar 54 and thereby locks the drawer in the closed position. It is obvious that the movement imparted to the lock plates and latch plates 25 in the operation of resetting the keys, has resulted in dropping the plates 96 and 109 to their normal positions and in raising the wedge shaped termination 52 of the extension 46^b of the department lock plate. It 30 will also be observed that these operations have resulted in the return of the finger pieces 44 to their normal positions.

When it is desired to open the drawer 35 without recording a sale or other transaction, the no sale key 32^b is depressed. Owing to the employment of the lifting lever 104, it will be observed that an inward pressure of the key stem 32^b will result in 40 tipping said lever and raising the plunger 90 out of the ball or roller case 35 thereby permitting the continued depression of said key stem. In this manner the department lock plate and latch plate will be operated 45 and the drawer released and thrown open without the necessity of depressing a value key.

I will now describe the operation of the transfer mechanism whereby amounts are 50 transmitted in tens from one registering wheel to another. Assuming that the registering wheels were originally set at zero, or that the zero or naught characters were displayed on the fronts of the registering 55 wheels immediately above the plate 198, it

is evident that the hereinbefore described operation of depressing the five cent key and opening and closing the drawer must have resulted in turning the cents registering wheel until the numeral 5 is displayed 70 at the point above mentioned. By assuming, now, that the next sale which it is desired to register, also amounts to five cents, said five cents key is again depressed and the drawer opened and closed in the manner 75 hereinbefore described. The last mentioned drawer closing operation must result, as will readily be seen, in the cents wheel being rotated until an additional five cents is registered thereon, or until five numerals have 80 passed the point of observation. This additional registration and movement of the cents wheel is such as to result in the display of a cipher at the point of observation 85 in place of the numeral 5, owing to the arrangement of the numerals on the wheel peripheries in groups or series of ten each. In addition to this result, the cents wheel has been moved sufficiently to cause an engagement of one of its peripheral contact 90 lugs 144 with the end of that pawl arm 178 which is arranged above the cents wheel, the point of said pawl arm passing said lug and being consequently raised thereby. The elevation thus imparted to the forward end of 95 the pawl arm 178, results, through the downward pressure of the rear portion of said arm against the pin 177, (see Fig. 22) in raising the hook end or head of the adjacent hook bar 174 out of engagement with 100 the head of the pawl 170, allowing the lower tooth or arm 171 of the latter to drop, by tension of its spring 176, into engagement with a tooth of the adjacent dimes wheel. When the drawer is again opened, it is obvious that the rearward swinging movement 105 which is imparted to the spring pressed trip bar 190 (see Figs. 6 and 4) will cause the upper end of the latter to successively engage 110 the depending triggers 165 of the shafts 163.

It will be seen that the contact above described of the trip bar and depending triggers must impart a partial rotation to the shafts 163, these shafts being, however, immediately returned to their normal positions 115 through the medium of the springs 179^a. In the present instance, the partial rotation which is imparted to the first of these shafts 163, and the consequent slight forward movement of the lever arm 166, is sufficient 120 to cause the dimes registering wheel to be moved the distance of one tooth or number, through the engagement of the pawl arm 171 therewith. In this manner the point of observation on the forward side of the cents wheel is made to display a cipher or naught character while the adjoining and opposite point on the dimes wheel will display the numeral 1, thus indicating that ten cents 125 has been registered. As the end of the trip 130

bar 190 moves out of contact with the last of the triggers 165, the lever branch arm 183 comes into contact with the lower end of the curved arm 188 and through the elevation thus imparted to said arm and the consequent lifting contact of the angle plate 187 with the upper arm 172 of the released pawl 170, said pawl is again raised to its normal position and engaged with the head 10 of the hook bar 174. Owing to the bevel of the upper end portion of the trip bar 190 and the corresponding inner faces of the triggers 165, it is obvious that the contact of said bar with said triggers which occurs during the closing of the drawer will only result in forcing said trip bar inward and admitting of its freely passing said triggers.

Although I have only described the operation of transferring from the cents to the dimes registering wheels, it is obvious that the same description will apply to the operation of transferring amounts from any one of said registering wheels to the other.

As a preventative for the overthrow of the registering wheels, I have provided the pawl or stop bar 196 between the beveled edge portion of which and the teeth of the registering wheels during the transfer operation are adapted to wedge the ends of the dropped pawl arms 171 thus preventing any further movement of the registering wheels. It is obvious that the engagement of the spring actuated pawls 195 with the teeth of the registering wheels, will operate to prevent a reversed rotation of said registering wheels.

In order to facilitate the resetting of the registering wheels to the zero points, I have provided the spring stop plate 198, the inner end of the latter when depressed projecting in the path of the radial projections 144 of the registering wheels and, by engagement with the latter, stopping a forced rotation of the registering wheels in positions to display the cipher signs thereon at the points of observation. This forced rotation of the registering wheels is accomplished by the successive raising and lowering of the arm 146 (see Fig. 24) which, through the successive engagement of the spring actuated bar 148 with the internal shoulders 145 of the registering wheels, will result in the desired rotation of the latter.

The manner of resetting the registering wheels or moving said wheels until the cipher characters thereon are displayed at the reading point, consists in depressing the stop plate 198 until its inwardly projecting end portion is in the path of the projections 144 on the registering wheels, then raising the yoke 146 until the dog or pawl arm 148 engages shoulders 145 of the registering wheels and forcing said yoke downward, thus rotating the registering wheels until 65 the projections 144 contact with the inturned

edge of the stop plate 198. The register wheels cannot be reset to zero, however, until after the drawer has been released, for, as will be seen most clearly by reference to Fig. 6, the operating pawls 152 are securely locked into engagement with the wheels when the drawer is closed by the engagement of the bell cranks 153 therewith. These bell cranks are at this time in engagement with the rod 157. Hence it is impossible for the operating pawls to be released until the drawer has opened and the operating yokes and the pawl carrying arms have dropped; and, as the register wheels cannot be reset to zero until the operating pawls have been unlocked, it follows that the yoke 146 cannot be depressed to set the register wheels to zero until the drawer has been opened. Inasmuch as the transferring from one register wheel to another takes place upon the opening movement of the drawer, it will be seen that the transfer is effected before the register is reset to zero.

It will be seen that owing to the connection heretofore described of the shaft arm 204 of the lower counter or recording device 203 with the swinging frame arm 85, the shaft of said counter will be subjected to an operation at each operation of opening the drawer.

The paper strip 236 from the reel 236 is, prior to the operation of the machine, run downward from said reel beneath the roller 217, thence beneath the frame plate 216 (see Fig. 11) from which point said strip passes above the platen head, thence beneath the guide pins 220 between the rollers 219 and 218 and out over the forward portion of the frame plate 216. From the plate 216, the paper strip is run on to the reel 238 having its end portion pressed in connection with the latter by the bar 241 shown in Fig. 35. Again assuming that the five cent value key, the initial A key and the department cash key have been depressed in the manner heretofore described, it is obvious that the dropping of those yokes 78 which belong to said key sets and which, as heretofore described, is occasioned by the drawer opening operation, will also result, through the connections of the yoke extensions 80 therewith, in the downward swinging movement of those printing segments which are connected with said yoke extensions, the degree of swinging movement of the printing segments being governed by the degree of movement of said yokes 78, and such movements resulting in bringing the type character 5 of the cents segment, 126 the initial character of the initial segment and the cash character of the department segment in alignment and position to receive the upward stroke of the platen head, in the manner hereinafter described. As the 130

drawer opens and the weighted yoke 83 descends, it will be seen that the spring actuated bar 261 of the printing mechanism, will be released from the contact and pressure of the pin 83^a of the finger 83^c of said weighted yoke. Through this release of the bar 261, the latter is allowed to swing forward until its block 259 contacts with the printer frame or keeper 257. The forward movement thus imparted to the spring actuated rod 256 results in moving the pawl 253 until its upwardly projecting tooth is in position for engagement with the ratchet wheel 242 of the receiving reel 238. This forward movement of the rod 256 and its bar extension 249 also results in the tooth of the pawl 248 being moved forward sufficiently to admit of its engagement with a new tooth of the ratchet wheel 242 of the roller 218. As the yoke finger 83^c continues its forward movement, it will be seen that the projecting pin 83^a thereof, in contacting with and moving beneath the outer end of the projecting pin or arm 265 of the lever 262, raises the latter and, through such movement, lifts the ink pad plate upward and presses the ink saturated pad thereof against those type faces which, as heretofore described, are arranged in position to contact with the platen head. Passing the lever projection 265, the pin projection 83^a, by engagement with the rear side or edge of the bar 232, moves the latter forward until its shoulder 233 is out of engagement with the pin 228. Thus relieved, the platen frame is, through action of the spring 231, thrown upward, the platen head pressing the paper strip against those type projections which are in line therewith. This release and upward movement of the platen frame also results, as will readily be seen, in the ink pad plate being carried to the rear and out of the way. The closing of the drawer and the consequent raising of the weighted lever 83 and the rearward and upward swinging movement of the finger 83^c, results in a contact of the finger pin 83^a with the upper end of the lever arm 229 and in starting the latter rearward. This rearward movement is continued and the platen frame thereby returned to its lower position and the pin 228 reengaged with the shoulder 233 through the contact of the curved lower end portion of the finger 83^c with said lever arm 229. In completing the upward movement of the weighted yoke, its finger pin 83^a comes into contact with and again forces the bar 261 rearward where it is retained until the next downward movement of said weighted yoke. In this rearward movement of the bar 261, it is obvious that the spring actuated rod 256 and its bar extension 249 will be moved rearwardly, with the result that, through the engagement of the pawl 253 with the ratchet wheel 242 and

the engagement of the pawl 248 with the ratchet wheel 246, said ratchet wheels have imparted thereto a partial rotation, which is sufficient to feed the printed portion of the paper a desirable distance forward and to wind a corresponding amount upon the reel 238. 13

In winding the printed portion of the paper strip on to the receiving reel 238, it is obvious that the circumference of the paper roll thus produced on said reel, will gradually increase and that, owing to the fact that the rotation of the reel, which is imparted through the engagement of the pawl 253 with the ratchet 242, is at all times uniform, the tendency of said enlarged roll will be to increase the length of paper which is taken up thereby. This difficulty I remedy by the employment of the spring actuated extension of said ratchet 242, it 85 being obvious that the additional or surplus movement of the said ratchet wheel, which is occasioned in the manner above described, will be taken up by said spring, the latter thus being gradually coiled. In this manner it will be seen that the actual rotary movement of the reel will be limited by the size of the coil of paper thereon and that when said reel is filled, the only result will be the increased tension of the spring 95 244. It is obvious that the reel is prevented from a reversed rotation by the engagement of a pawl 242 with the teeth of said ratchet. 90

It is obvious that the closing of the drawer and the consequent raising of the yokes 78 will also result in the raising of the dropped printing segments to their normal positions. 100

Having now fully described my invention, what I claim and desire to secure by Letters Patent is—

1. In a cash register, the combination with a series of adding wheels and a series of numbered or value keys, of a series of initial keys, department keys, and a no-sale key and locking means under the control of the value keys whereby the no-sale key cannot be operated if a value key has first been depressed. 110

2. In a cash register, the combination with a key frame, sets of depressible value and department keys, therein and a no-sale key comprised in said set of department keys, of a locking device which prevents the depression of said department keys until a cash key has been depressed and connections between said no-sale key and said locking device which releases the latter by a depression of said no-sale key, substantially as specified. 115

3. A cash register having a series of adding wheels, and a series of numbered or cash keys in combination with a series of initial keys and a no-sale key and one or more department keys with locking means to prevent the operation of any of the keys when the no-sale key is depressed, substantially as specified. 125

4. A cash register having a series of adding wheels and a series of numbered or cash keys in combination with a series of initial keys and a no-sale key and one or more normally undepressible department keys, means for unlocking the department keys and means for preventing registration by either the numbered keys or initial keys until a department key has first been operated, substantially as specified.
5. In a cash register, the combination with a key frame, sets of value keys and a no-sale key mounted therein, of a movable lock bar 98 and mechanism between the latter and said cash keys whereby the depression of a value key moves said locking bar 98 into position to prevent the depression of the no-sale key, substantially as specified.
6. In a cash register, the combination with a key frame, a set of depressible value keys therein and a depressible no-sale key having a pin projection 101, of a fulcrumed lever plate 96, a locking arm 98 jointedly connected therewith, and a device which through the depression of a value key lifts said fulcrumed plate 96 and projects the arm 98 into the path of the no-sale key stem pin, substantially as specified.
7. In a cash register, the combination with a key frame, sets of depressible value and department keys therein and a no-sale key comprised in said set of department keys, of a roller containing case arranged in the path of the stems of the department and no-sale keys, a plunger 90 which together with said rollers so fill said case as to prevent the depression of one of said department keys and connections between said no-sale key whereby the depression thereof lifts said plunger out of said roller case, substantially as specified.
8. In a cash register, the combination with a key frame, and sets of value and department keys therein, of a roller containing case arranged in the path of the stems of the department keys, a plunger 90 which together with said rollers so fills said case as to prevent the depression of one of said department keys, a journaled bar 93 having an arm jointedly connected with said plunger and means whereby the depression of a department key lifts said bar 93 and its arm sufficiently to raise said plunger out of said roller case, substantially as specified.
9. In a cash register, the combination with a key frame and a key 32^b mounted therein, said key having a laterally projecting pin 101, of a roller containing case arranged opposite the stem of said key, a plunger projecting in said case, said plunger together with the rollers therein filling said case and a fulcrum lifting lever jointedly connected with said plunger and having one end supported in the path of said key stem pin, substantially as specified.
10. In a cash register, the combination with a key frame, depressible value keys and depressible department keys mounted therein and a connection between said department keys and each set of value keys whereby the depression of a department key following the depression of a value key locks the remaining value keys of the set to which the depressed key belongs against depression, substantially as specified.
11. In a cash register, the combination with a key frame, sets of value and department keys therein and a department key set latch plate, of a journaled bar or plate 109, and a lock plate for each set of value keys, said bar or plate 109 adapted by the movement imparted to the department latch plate through a depression of a department key to engage said value key lock plates, substantially as specified.
12. In a cash register, the combination with a key frame, and sets of depressible value and department keys therein, of a department latch plate 46 operated by the depression of a department key, a journaled bar or plate 109 having hub recesses and a lock plate for each set of value keys, said department latch plate adapted by the operation of a department key to move said plate or bar 109 and produce an engagement of said value key lock plates with the hub recesses thereof, substantially as specified.
13. In a cash register, the combination with a key frame and sets of value and department keys therein, of fulcrumed lock and latch plates for each of said key sets and operated thereby, a fulcrumed gravity hook piece for each of said lock plates, a journaled plate 109 normally retaining said hook pieces in raised positions and connections between said plate 109 and the department latch plate, whereby the depression of a department key following the depression of a value key permits the hook piece which belongs to a value key set which contains a depressed key to drop into engagement with the corresponding lock plate, substantially as specified.
14. In a cash register, the combination with a framework, sets of depressible keys, lock plates adapted to lock said keys in depressed positions, a sliding cash drawer, a guide bar mounted on said drawer, a lug on said guide bar, a resetting frame cooperating with said lock plate, a fulcrumed trip lever engaging said resetting frame, and a cam flange on said trip lever, said flange being adapted to contact with and be operated by the lug on the guide bar during the closing movement of the drawer for operating said resetting frame and elevating said lock plates, for the purpose specified.
15. In a cash register, the combination with a framework, sets of depressible keys

- therein, a lock plate for each set of said keys, said lock plates being adapted to drop on the depression of said keys and to temporarily hold the latter in their depressed positions, a sliding cash drawer, a guide bar on said drawer, said bar having a lug projecting therefrom, a full-stroke rack secured to the framework, a full-stroke pawl pivoted to the guide bar and engaging 5 with the rack, a fulcrumed resetting yoke, a fulcrumed trip lever engaging said resetting yoke, and an inclined projection on the trip lever, said projection being arranged in the path of the lug on the guide bar, 10 whereby, as the drawer is closed, the trip lever is operated to lift the resetting yoke and the lock plates for releasing the depressed keys.
16. In a cash register, the combination 20 with a framework, sets of depressible value and department keys therein, and value and department key locking devices, of a sliding cash drawer, and independent devices operated by the closing of said cash drawer 25 for resetting the value and department key locking devices, substantially as specified.
17. In a cash register, the combination with a framework, sets of depressible value and department keys mounted therein, value 30 and department key locking devices and a department key locking device, a fulcrumed trip lever adapted by contact with a drawer projection to raise said value key locking devices, a trip plate having an inclined projection 35 in the path of said drawer projection, a swinging frame connected with said trip plate, said frame having an arm which extends beneath the department key locking device, substantially as specified.
- 40 18. In a cash register, the combination with a framework, one or more sets of depressible value and department keys therein, of a sliding cash drawer, a fulcrumed drawer latch bar adapted by engagement 45 to retain said drawer in its closed position, a fulcrumed latch plate operated by the depression of a department key and an extension on said latch plate having means thereon for holding the department keys 50 in depressed positions, said plate being adapted when the latter is operated to move said latch bar out of engagement with the drawer, substantially as specified.
19. In a cash register, the combination 55 with a framework, one or more sets of depressible value and department keys and a sliding drawer, of a spring actuated locking bar adapted to retain said drawer in a closed position and a fulcrumed department 60 latch plate operated by the depression of a department key, said latch plate having a beveled termination adapted when depressed to press said drawer latch bar out of engagement with the drawer, substantially as specified.
20. In a cash register, registering devices, operating mechanism for said devices, a cash drawer for operating said mechanism, a bracket secured to said cash drawer, a roller in said bracket for engaging the operating mechanism, and a set-screw passing through the bracket and engaging the drawer for adjusting the bracket with respect to the drawer, whereby the proper degree of movement may be imparted to 75 said operating mechanism.
21. In a cash register, a cash drawer, a series of value keys, a series of special keys, means for locking said keys when depressed, and means controlled by the cash drawer 80 for unlocking the keys of both series, the keys in the special series being unlocked prior to the keys in the value series.
22. In a cash register, a cash drawer, a series of value keys, a series of special keys, 85 means for locking said keys when depressed, and means controlled by the cash drawer for unlocking the keys of both series, the special keys being unlocked at the beginning of the inward movement of the cash drawer, 90 and the value keys being unlocked near the termination of said inward movement of the cash drawer.
23. In a cash register, a main operating member, a series of value keys, a series of 95 special keys, means for locking said keys when depressed, and means controlled by the main operating member for unlocking the keys of both series, the special keys being unlocked at the beginning of one movement 100 of the main actuating member, and the value keys being unlocked near the termination of said movement of the main actuating member.
24. In a cash register, the combination 105 with a key frame and adjacently arranged sets of depressible value and department keys therein and means for preventing a depression of a department key until a value key has been depressed, of value registering wheels, printing mechanism comprising department and value printing devices, and mechanism whereby the extent of operation 110 of the registering and printing devices is governed by the value and department keys 115 depressed, substantially as set forth.
25. In a cash register, the combination with a sliding drawer, a key frame and adjacently arranged sets of value and department keys 120 therein, of value registering wheels, printing mechanism comprising department and value printing devices, means whereby the opening and closing of the cash drawer produces an operation of said registering and printing mechanism and 125 mechanism whereby the extent of operation of said registering and printing mechanism is governed by the value and department keys depressed, substantially as set forth.
26. In a cash register, the combination 130

with a framework, sets of depressible value, initial and department keys, a swinging frame 78 for each set of said keys, said frame provided with journaled extensions and each 5 of said extensions carrying a printing segment, and mechanism between the keys and said frames which limits the movement of the latter, of a swinging frame 83 carrying a projecting finger and a printing mechanism 10 coöoperating with said printing segments and adapted to be operated by said finger, substantially as specified.

27. In a cash register, a set of swinging printing segments and means for independently dropping said segments to a printing position, of a fulcrumed platen, a receiving reel for a paper strip, paper strip feed rolls, a ratchet wheel on one of the latter, a spring actuated reciprocating feed bar 249, a pawl thereon engaging said ratchet wheel and a device connected with the cash register for operating said feed bar, substantially as specified.

28. In a cash register, the combination 25 with a framework, and a set of independently operated printing segments mounted therein, of a swinging platen, a paper feed roller carrying a ratchet wheel, a paper receiving reel carrying a ratchet wheel, a fulcrumed and reciprocating feed bar having a pawl engaging the feed roller ratchet wheel and a pawl carried on said feed bar adapted when the latter is operated to engage said receiving reel ratchet and means 30 connected with the cash register for operating said platen and feed bar, substantially as specified.

29. In a cash register and printing mechanism therefor, the combination with a registering and printing mechanism of a receiving reel for a paper strip, the latter comprising a frame pin 237, a flanged reel tube journaled thereon, a ratchet wheel journaled on said pin, a coiled spring carried 45 by said ratchet wheel and having one end connected with said reel and means for imparting motion to the ratchet wheel, substantially as specified.

30. In a tape printer, the combination of 50 movable printing segments, a fulcrumed inking device, means for positively operating said device, a swinging platen, a tape supply reel carrying a tape roll, a tape receiving reel, tape guide and feed rolls, keys 55 for controlling the movements of said printing segments, and means for operating said platen, and receiving reel.

31. In a cash register and printing mechanism therefor, a paper strip receiving reel 60 consisting of a frame pin 237 provided with a longitudinal recess, a spring strip secured therein and projecting therefrom and a tubular reel body mounted on said pin, substantially as specified.

32. In a cash register, the combination 65 with a framework, a set of depressible keys and a rotary indicator, of a swinging frame the movement of which is limited by the key depressed, a fulcrumed spring actuated gear segment having a gear connection with 70 said indicator, and a rod having a pivotal connection with an arm of said segment and with said swinging frame, substantially as specified.

33. In a cash register, the combination 75 with a framework, depressible keys therein and a rotary target or indicator, of a swinging frame the extent of movement of which is governed by the key depressed, a gear segment having a spring actuated hub and a 80 gear connection with said indicator, and a rod jointedly connecting an arm of said gear segment with said swinging frame, substantially as specified.

34. In a cash register, the combination 85 with a framework, depressible value and department keys therein, rotary targets or indicators, ratchet wheels connected therewith, a shaft and pawls carried thereon, said pawls normally engaging said ratchet 90 wheels and a spring actuated shaft arm 133, of a spring actuated bolt normally engaging said shaft arm and retaining said pawls in engagement with said ratchet wheels and connections between said department keys 95 and said bolt whereby the latter is withdrawn by the depression of a department key, substantially as specified.

35. In a cash register, the combination 100 with sets of depressible value and department keys, rotary indicators having ratchet wheels and springs normally retaining said indicators in positions for displaying the cipher signs thereon, of pawls adapted to engage said ratchet wheels, a locking mechanism adapted to retain said pawls in connection with said ratchets and connections between the department keys and said locking mechanism whereby the latter is released through a depression of a department 105 key, substantially as specified.

36. In a cash register, the combination 110 with a framework, depressible keys therein, rotary targets or indicators, ratchet wheels connected therewith, a shaft and pawls carried thereon, said pawls normally engaging said ratchet wheels and an arm 133 depending from said pawl shaft, of a gravity frame having a cam arm 85, the latter having upper and lower cam ways or paths in 120 which is adapted to travel a pin of said arm 133 and means for operating said swinging frame, substantially as specified.

37. In a cash register, the combination 125 with a framework, depressible value and department keys therein, rotary targets or indicators, means for operating the same, ratchet wheels connected therewith, a shaft

and pawls carried thereon, said pawls normally engaging said ratchet wheels and a spring actuated arm 133 depending from said pawl shaft and provided with a projecting pin, of a gravity frame having a cam arm 85, the latter having a cam way or path within which said arm pin is adapted to project and travel, a spring actuated bolt 137 normally engaging said pawl shaft arm, thereby holding the pawls in engagement with said ratchet wheels and connections between said bolt and the department keys whereby a depression of one of the latter results in the withdrawal of said bolt and release of said ratchet wheels, substantially as specified.

38. In a cash register, the combination with a registering mechanism, of a series of yokes, a main lever for operating the same, 20 register operating devices actuated by the yokes, a series of indicators, operating devices for the indicators, unlocked links between the indicators and the yokes, and means for actuating the links to move the indicators upon the initial stroke of the main operating lever.

39. In a cash register, the combination with a series of operating yokes, of a main lever for operating the same, a series of 30 indicators, a series of indicator operating segments having links loosely attached to the operating yokes for moving said indicators to operated position, springs for returning the indicators to normal position, 35 selective devices for operating the main lever, and means intermediate the main lever and the indicator links for operating the latter upon the initial movement of said main lever.

40. 40. In a cash register, the combination with a series of operating yokes, of springs for actuating said yokes to initial position, 45 of an oscillatory lever for returning the same to normal position, a series of indicators, loose link connections between the operating yokes and indicators for setting the indicators upon the initial movements of the operating yokes, and means intermediate the main operating lever and the links for 50 operating the latter upon the initial stroke of the operating yokes.

41. In a cash register, the combination with a series of adding wheels, a series of operating yokes, a series of indicators, a 55 series of oscillating segments for the indicators, a series of loosely connected links between said segments and yokes for setting the indicators upon the initial movement of the yokes, studs mounted on the yokes for 60 moving the links, segments and indicators to operated position, springs for returning the indicators to normal position, register operating devices actuated upon the return movement of the yokes, a main operating

lever for returning the yokes to normal position after the indicators have come to rest. 65

42. In a cash register and recorder, the combination with a registering mechanism, of a series of yokes, a main lever for operating the same, register operating devices actuated by the yokes, a series of indicators, 70 operating segments for the indicators, a spring for returning the segments and indicators to normal position, and an unlocked link connection between the yokes and the 75 operating segments adapted to set the indicators upon the initial movement of the operating yokes.

43. In a cash register, the combination with a registering mechanism, of a series of 80 yokes, a main lever for operating said yokes, register operating devices actuated by said yokes, a series of indicators, operating segments for said indicators, a spring for returning the segments to normal position, 85 and a link connecting the yokes to the operating segments, adapted to set the indicators upon the initial movement of the operating yokes.

44. In a combined register, indicator and recorder, having reciprocating depressible setting keys for values, initials and departments, one or more sets of type, a roll of paper, a printing mechanism, a feeding mechanism, and selective means for operating both of said mechanisms. 90

45. In a cash register, a framework, a cash drawer mounted to slide in a chamber in said framework, and a spring plate mounted on said framework and projecting 100 into the drawer chamber, said plate being adapted to engage with the drawer as it approaches the end of its movement in one direction, whereby the said movement is checked.

46. In a cash register, a framework, registering mechanism, a cash drawer mounted to slide in a chamber in said frame work, a spring plate mounted on said framework and projecting into the drawer chamber, 110 said plate being adapted to engage with the drawer as it approaches the end of its movement in one direction, whereby the said movement is checked, and means operated by said drawer for operating the registering 115 mechanism.

47. In a cash register, a series of registering wheels, arms pivoted coaxially with said wheels, actuating pawls carried by said arms and engaging said wheels, locking members 120 carried by said arms and adapted to engage the actuating pawls for locking the same to the registering wheels, auxiliary yokes for lifting the said arms for turning the registering wheels, a main actuating lever for 125 lifting the said auxiliary yokes, a cam connected with said lever, and connections between said cam and said locking members.

for controlling the latter whereby the actuating pawls may be locked and unlocked from the registering wheels.

48. In a cash register, the combination with a set of numbered registering wheels, the inner side of each of said wheels being provided at intervals with shoulders, a fulcrumed lever frame 146 and spring actuated dogs carried by said frame and adapted when the latter is moved upward to engage the internal shoulders of said wheels, substantially as specified.

49. In a cash register, the combination with a set of number registering wheels having internal shoulders arranged at intervals and peripheral projections 144, of a swinging frame 146, dogs carried thereon and adapted to engage said shoulders when said frame is lifted and a stop plate mounted adjacent to said wheels and adapted to be projected in the path of said peripheral projections, substantially as specified.

50. In a cash register, the combination with a series of adding wheels, of a series 25 of value, initial and department keys, and oscillatory indicators, locking means under control of the initial or department keys to lock the indicators into positive position, predetermined by the keys depressed.

51. In a cash register a series of indicating and registering devices, value and department keys adapted to determine the movement of the registering and indicating devices, a normally closed cash drawer and 35 a catch therefor, in combination with a swinging frame adapted to release the drawer catch upon the depressing of a department key.

52. In a cash register the combination of 40 a series of normally unlocked initial and value keys, a series of normally locked department keys, and a normally unlocked no-sale key, with locking means controlled by the no-sale key for preventing the depression of either a value, initial or department key after the no-sale key has been depressed.

53. In a cash register, the combination in 45 a key-frame of a no-sale key and two species of depressible keys therein, the first species comprising normally depressible keys for both values and initials, the second species comprising normally indepressible department keys, with means under control of the no-sale key to prevent the depression of either a value key, initial key or department key after the no-sale key has been depressed.

54. In a cash register, the combination in 50 a key-frame of a single or special no-sale key and two distinct sets of depressible keys therein, the first set comprising normally unlocked value and initial keys, the second set comprising normally locked department

keys, and means under control of either a 65 value or an initial key adapted, when depressed, to unlock the normally locked department keys and prevent the depression of the no-sale key.

55. In a cash register, the combination in 70 a key-frame of a no-sale key and two distinct sets of depressible keys therein, the first set comprising normally unlocked value and initial keys, the second set comprising normally locked department keys, 75 and means under control of either a value or an initial key to prevent the release of the department keys until either an initial or a value key or both have been depressed.

56. In a cash register, indicator and recorder, the combination with type characters for printing values, initials and departments, of two distinct sets of depressible keys therein, the first set comprising normally unlocked value and initial keys, 85 the second set comprising normally locked departmental release keys, and means requiring the depression of a value key or an initial key, or both, and a department key before a commercial transaction can be indicated and recorded.

57. In a recording cash register, printing mechanism having a movable type member, a swinging segment connected thereto, a series of normally unlocked keys for limiting the movements of said segment, a detent for said keys, a lock for said detent, means for actuating said segment, and for unlocking said detent, and means for moving the detent to release the keys, substantially as specified.

58. In a cash register, the combination with normally unlocked value and initial keys forming one series, and a normally locked group of department keys forming 105 a second series, printing mechanism having movable type members, swinging segments connected thereto, keys for limiting the movement of said segments, a catch for said keys, a lock for said catch, and means for 110 actuating said segments and unlocking said catch to release the caught keys after use in the order predetermined.

59. In a cash register, indicator and recorder, the combination with type characters for recording values, initials and departments, of two sets of depressible keys therein, the first set comprising normally unlocked value and initial keys, the second set comprising normally locked departmental release keys, and mechanism requiring the depression of a value key initial key and departmental release key before the 115 salesman of a credit transaction can be identified in the record as indicated.

60. In a cash register, indicator and recorder, the combination with type characters for recording values, initials and de-

partments, of two sets of depressible keys therein, the first set comprising normally unlocked value and initial keys, the second set comprising normally locked departmental release keys, and mechanism requiring the depression of a value key, initial key and departmental release key before the salesman of a cash transaction can be completely identified in the record as it was indicated.

61. In a cash register, the combination with a registering mechanism, of a series of normally operative value setting elements, means under control of said elements for controlling the registering mechanism, a series of normally operative clerk's setting elements, said latter elements being independent of the registering mechanism, means for locking the elements of either of said series when operated in any order, a series of normally operative transaction setting elements, and means to compel the use of one or more of the normally operative series before the normally inoperative series can be rendered operative.

62. In a cash register, the combination with a registering mechanism, of a series of normally operative value setting elements, means under control of said elements for controlling the registering mechanism, a series of normally operative clerk's setting elements said latter elements being independent of the registering mechanism, means for locking the elements of either of said series when operated in any order, a series of normally inoperative transaction setting elements, and means to prevent the use of the normally inoperative series until one or both of the normally operative series has been operated.

63. In a cash register, indicator and recorder, the combination with a registering mechanism, an indicating mechanism and a recording mechanism connections between said setting elements and each of the registering, indicating and recording mechanisms whereby said mechanisms are controlled from said elements, a series of normally operative clerk's setting elements, connections between said latter elements and the indicating and recording mechanisms whereby said two mechanisms are further controlled by said clerk's setting elements, said latter elements being independent of the registering mechanism, means for locking the elements of either of said series when operated in any order, a series of normally

inoperative transaction setting elements before a transaction setting element can be used, and before the register, indicator and recorder can be actuated.

64. In a cash register and recorder, the combination with a normally locked operating member of registering and recording mechanisms, a series of normally operative value setting elements, connections between said elements and the registering and recording mechanisms whereby said mechanisms are controlled from said elements, a series of normally operative clerk's setting elements, connections between said latter elements and the recording mechanism, whereby the latter is further controlled by the clerk's setting elements, the latter elements being independent of the registering mechanism, means for locking the elements of either of said series when operated in any order, a series of normally operative transaction setting elements, means whereby the operation of a transaction setting element releases the operating member and means to compel the operation of a value setting element before the transaction setting element can be used to release the operating member to register and record the nature and amount of a transaction.

65. In a cash register and recorder the combination with a normally locked operating member of registering and recording mechanisms, a series of normally operative value setting elements, connections between said elements and the registering and recording mechanisms whereby said mechanisms are controlled from said elements, a series of normally operative clerk's setting elements, connections between said latter elements and the recording mechanism whereby the latter is further controlled by the clerk's setting elements the latter elements being independent of the registering mechanism means for locking the elements in either of said series when operated in any order, a series of normally inoperative transaction setting elements, and means to prevent the release of the normally locked printing member until either a value setting element or a clerk's setting element has been used to release the transaction setting element.

HENRY S. HALLWOOD.

In the presence of—

ANNA G. BAGLEY,
H. B. BRADSHAW.

BEST AVAILABLE COP

Correction in Letters Patent No. 1,078,920.

It is hereby certified that Letters Patent No. 1,078,920, granted November 18, 1913, upon the application of Henry S. Hallwood, of Columbus, Ohio, for an improvement in "Cash-Registers," were erroneously issued to The Hallwood Cash Register Company, as owner of the entire interest in said improvement, whereas said Letters Patent should have been issued to *Annie Hallwood, of Columbus, Ohio* as assignee by means assignments of the said invention, as shown by the records of assignments in this office; and that the said Letters Patent should be read with this correction therein that the same may conform to the record of the case in the Patent Office.

Signed and sealed this 10th day of February, A. D., 1914.

[SEAL]

J. T. NEWTON,

Acting Commissioner of Patents.
